GEORGE H. PARSONS, OF STAMFORD, CONNECTICUT, ASSIGNOR TO KROEGER PIANO COMPANY, OF STAMFORD, CONNECTICUT, A CORPORATION OF NEW YORK.

ACCENTING DEVICE FOR PLAYER-PIANOS.

1,209,199.

Specification of Letters Patent.

Patented Dec. 19, 1916.

Application filed October 26, 1914. Serial No. 868,564.

To all whom it may concern:

Be it known that I, GEORGE H. PARSONS, a subject of the King of Great Britain, residing at Stamford, county of Fairfield, State of Connecticut, have invented an Improvement in Accenting Devices for Player-Pianos, of which the following is a specification.

This invention relates to player pianos and has for its object to provide an accenting device which will enable the performer to place any desired accent upon any note or notes by means of the pedals. In other words the player produces the required accent by regulating the degree and quickness of the pressure of the feet on the pedals.

In the accompanying drawings forming a part of this specification, Figure 1 is a perspective illustrating the application of my novel accenting device to a player piano; Fig. 2 a sectional view on a plane indicated by the dotted line 2—2 in Fig. 1, looking in the direction of the arrows, and Fig. 3 is an elevation of the accenting valve as seen 25 from the right in Fig. 2.

10 denotes frame work within the piano case, not shown, 11 the key bed, 12 the main bellows from which operating connections extend to the pedals 14, 15 a duct or air passage leading from the main bellows to the equalizing bellows, indicated by 16, 17 springs normally acting to retain the equalizing bellows distended, and 18 a pipe leading from duct 15 to the striker-pneumatic 30 wind chest, not shown, all of which parts are in common use in player pianos.

It is of course well understood by those familiar with the art that the action of the 40 pedals is to partially exhaust the main bellows, the equalizing bellows and the wind chest, in fact to partially exhaust the entire pneumatic system. When a perforation in a record (not shown) registers with a port in the tracker bar (not shown), air rushes 45 into the pneumatic system and by means of mechanism, not shown, causes the playing of a note. The function of the equalizing bellows is to equalize the vacuum tension in the pneumatic system. The performer can of course produce an accenting effect to a limited degree by the degree and quickness of his pressure upon the pedals. The effect is quite limited, however, for the reason that the direct action of increased pressure is 50 against the springs of the equalizing bellows,

which act to keep said bellows distended. The equalizing bellows, in fact, take up to a great extent the effect of added or quickened pressure on the pedals.

The object of my present invention is to 60 retain to the fullest extent the equalizing function of the equalizing bellows and in addition to enable the performer to accent notes when required. This I accomplish by means of additional bellows 19, which I 65 term the accenting bellows, and which are connected by means of a pivoted link 20 with the equalizing bellows. The back of the accenting bellows is provided with an opening 21 which is adapted to be closed by 70 a valve 22 controlled by means of an accent lever 23 and intermediate connections. The accent lever is placed in a suitable position to adapt it for manipulation by the performer. In the present instance the accent 75 lever is shown as rigidly secured to an oscillatory rod 24 having an arm 25. This arm is connected by means of a link 26 to an arm 27 which projects from the valve. A spring 28 connected to arm 27 and to any 80 fixed member, in the present instance to the key bed, acts to normally retain the valve in the open position as in Fig. 2, and likewise to retain the accent lever in its normal or inoperative position.

The operation is as follows: In ordinary use, operation of the pedals causes the equalizing bellows to close, and the instant the vacuum tension is relieved, said bellows are 85 opened by the springs 17. Under these conditions, that is in ordinary use, the accenting bellows are inoperative, valve 22 remaining open and the swinging member thereof, indicated by 29, which is connected by link 20 to the swinging member of the equalizing 90 bellows, indicated by 30, causing the pivoted members of said bellows to move in unison. Suppose now that the performer desires to accent a note. He swings accent lever 23 to the operative position against the power of 95 spring 28 which moves valve 22 to the closing position. The effect of this is to stop the entrance of air into the accenting bellows or the escape of air therefrom (depending of course upon which way swinging member 29 of the accenting bellows is moving) and, as the swinging members of the 100 two bellows are connected by link 20, to practically arrest the movement of the swinging members of both bellows in what- 105 110

ever position they may be at the instant the accent lever is operated. In other words, any slight movement of the equalizing bellows that may be possible while the accent lever 23 is retained in its operative position against the power of spring 28, will be insufficient to have any appreciable effect upon the operation of the instrument, and hence the closing of the opening 21 has the effect of rendering the bellows 16 inoperative to the extent that it cannot perform its normal functions. With the equalizing bellows inoperative, as above stated, it follows that increased or quickened pressure upon the 15 pedals will instantly increase the vacuum tension, and the note or notes played while accent lever 23 is held in operative position will be given a marked accent depending upon the quickness and amount of pressure applied to the pedals. To accent a single note the operator simultaneously imparts a quick movement to the accent lever, instantly releasing it, and a quick acceleration of pressure to one of the pedals. The instant pressure upon the accent lever is relieved, spring 28 will return said lever to its normal position and open valve 22, as in Fig. 2, the effect of which is to instantly render the equalizing bellows operative again, so that ordinary variations in pressure upon the 25 pedals will be taken up by the equalizing bellows and will have no appreciable effect upon the vacuum tension.

Having thus described my invention I claim:—

1. In a player piano, the combination with main bellows and equalizing bellows, of an accenting bellows, a connection between said accenting bellows and the equalizing bellows, an accent lever, and connections oper-

ated by the accent lever for closing said accenting bellows, whereby substantial movement of the equalizing bellows is prevented.

2. In a player piano, the combination with main bellows and equalizing bellows, of an accenting bellows, a pivoted link connecting the swinging members of the accenting bellows and the equalizing bellows, an accent lever and connections operated thereby for closing said accenting bellows to substantially arrest movement of the swinging members of the accenting and the equalizing bellows.

3. In a player piano, the combination with main bellows and equalizing bellows, of an accenting bellows, a link connection between the swinging members of the equalizing and the accenting bellows, a valve controlling the entrance of air to the accenting bellows, an accent lever and operating connections between said lever and the valve.

4. In a player piano, the combination with main bellows and equalizing bellows, of an accenting bellows, a link connection between the swinging members of the accenting and the equalizing bellows, a valve controlling the entrance of air to the accenting bellows, an arm extending from said valve, an accent lever, an oscillatory rod to which said lever is secured and which is provided with an arm, a link connecting the arms of the lever and the valve and a spring acting to retain the valve in the open position and the accent lever in its inoperative position.

In testimony whereof I affix my signature in presence of two witnesses.

GEORGE H. PARSONS.
